Primary Examiner — Jack Reickel*Assistant Examiner* — Russell Carnell Smith, Jr.(74) *Attorney, Agent, or Firm* — Kunzler Bean & Adamson, PC; Bryan Pitt(57) **CLAIM**

The ornamental design for a data cable, as shown and described.

DESCRIPTION

FIG. 1 is a front, top and right side perspective view of a data cable showing my new design;
FIG. 2 is a rear, top and left side perspective view thereof;
FIG. 3 is a top, rear and right side perspective view thereof;
FIG. 4 is a front elevational view thereof;
FIG. 5 is a rear elevational view thereof;
FIG. 6 is a right side elevational view thereof;
FIG. 7 is a left side elevational view thereof;
FIG. 8 is a top plan view thereof;
FIG. 9 is a bottom plan view thereof;
FIG. 10 is an enlarged view of portion 10 in FIG. 1;
FIG. 11 is an enlarged view of portion 11 in FIG. 2;
FIG. 12 is an enlarged view of portion 12 in FIG. 3;
FIG. 13 is an enlarged view of portion 13 in FIG. 5;
FIG. 14 is an enlarged view of portion 14 in FIG. 6;
FIG. 15 is an enlarged view of portion 15 in FIG. 8; and,
FIG. 16 is an enlarged view of portion 16 in FIG. 9.
The broken lines show the features of the data cable that form no part of the claimed design.

1 Claim, 16 Drawing Sheets(56)
